US0D1097828S

(12) **United States Design Patent** (10) Patent No.: **US D1,097,828 S**
(45) Date of Patent: ** Oct. 14, 2025

(54) **FOOD PRODUCT PACKAGING**

- (71) Applicant: **Impossible Foods Inc.**, Redwood City, CA (US)
- (72) Inventors: **Ravi Vasant Thakkar**, Santa Clara, CA (US); **Bruce Bitowft**, San Francisco, CA (US); **Eyal Briller**, Menlo Park, CA (US)
- (73) Assignee: **Impossible Foods Inc.**, Redwood City, CA (US)
- (**) Term: **15 Years**
- (21) Appl. No.: **29/936,557**
- (22) Filed: **Apr. 9, 2024**

Related U.S. Application Data

- (63) Continuation of application No. 29/817,640, filed on Dec. 2, 2021, now Pat. No. Des. 1,027,634, which is a continuation of application No. 29/746,884, filed on Aug. 18, 2020, now Pat. No. Des. 999,638, which is a continuation-in-part of application No. 29/714,451, filed on Nov. 22, 2019, now Pat. No. Des. 1,023,758.

(57) **CLAIM**

The ornamental design for a food product packaging as shown and described.

DESCRIPTION

FIG. 1 is a top perspective view of a food product packaging showing our new design;

FIG. 2 is a first side view thereof;

FIG. 3 is a second side view thereof; and,

FIG. 4 is a top plan view thereof.

The broken lines in the figures represent unclaimed subject matter and form no part of the claimed design. The shading lines used in the figures indicate contour.

1 Claim, 4 Drawing Sheets
